(57) **CLAIM**

The ornamental design for a webbing system with supports, as shown and described.

DESCRIPTION

FIG. 1 is a bottom perspective view of a webbing system with supports with the evenly spaced broken lines representing stitching and forming part of the claimed design.

FIG. 2 is a front elevation view of FIG. 1.

FIG. 3 is a back elevation view of FIG. 1.

FIG. 4 is a top plan view of FIG. 1.

FIG. 5 is a bottom plan view of FIG. 1.

FIG. 6 is a right side plan view of FIG. 1.

FIG. 7 is a left side plan view of FIG. 1.

FIG. 8 is a detailed bottom perspective view of the webbing connected to the support, shown twice the size of FIG. 1 for clarity of illustration.

FIG. 9 is a front and back side elevation view thereof shown twice the size of FIG. 2 for clarity of illustration.

FIG. 10 top plan view thereof shown twice the size of FIG. 4 for clarity of illustration; and,

FIG. 11 is a right side elevation view thereof shown twice the size of FIG. 6 for clarity of illustration.
